DESIGN FOR AN ADVERTISING CARD

James Fremont Sanford, Colorado Springs, Colo.

Application June 20, 1936, Serial No. 63,403

Term of patent 3½ years

To all whom it may concern:

Be it known that I, James Fremont Sanford, a citizen of the United States, residing at Colorado Springs, in the county of El Paso and State of Colorado, have invented a new, original, and ornamental Design for an Advertising Card of which the following is a specification, reference being had to the accompanying drawing, forming part thereof.

The figure is a plan view of an advertising card showing my design which consists of thirteen links united to form a unit.

I claim:

The ornamental design for an advertising card, substantially as shown and described.

JAMES FREMONT SANFORD.
